UNITED STATES PATENT OFFICE

FERDINAND E. KAUFFMANN, OF RAHWAY, NEW JERSEY

HAT BLOCK

Application filed March 19, 1928. Serial No. 262,703.

This invention relates to an improved hat block and is particularly designed for supporting hats when being treated as in clipping or at any operation in which it is desired that the hat body be supported with a slight cushion effect.

The invention is also designed to hold a hat body with the necessary tension but to allow an easy placing or removal of the hat body. This is especially desirable in the case of hats that are thin and which are sometimes torn or the surface wrinkled when the hat body is forced over a hat block of the old style.

15 The invention consists of a hat body with a flexible cover which is only slightly larger than the block when air under pressure is admitted to the space or passage between the body of the block and the cover. This small space not only allows a quick inflation and deflation of the cover on account of the small amount of air used to inflate it but the cushioning is not excessive and the hat body is supported with enough tension and stiffness 25 to make clipping and other operations easy as the hat body is cushioned but taut.

30 The invention is illustrated in the accompanying drawings in which Figure 1 is a section of a hat block made according to my invention. Figure 2 is a similar section of a modified form.

35 In the drawings the hat block is shown at 10 and it is secured by any suitable means such as a screw-threaded means 11 to a shaft or support, or it can be placed directly on the table when this is desired.

40 On the hat block is arranged a cover usually of rubber although any other flexible material can be used and this provides a spaced passage or chamber to which air is admitted, the air being under pressure to the desired extent. Over that part of the hat block on which the hat is placed I arrange a covering which in Figure 1 consists of double walls, an inner wall 12 to fit over the hat block and an outer wall 13 spaced from the inner wall so as to form a narrow chamber or passage 14. Air under pressure can be admitted to this passage by means of a valve 45 15 of any usual form such as a tire valve and

through the same medium the air can be released. It will be evident that when the cover is deflated the hat body 16 can be easily slid over it and then air is forced beneath the cover or sheet 13 and the hat block is inflated to hold the crown of the hat body taut and shaped. In this condition it can be easily operated on such as in hat clipping in which the workman passes a clipper over the surface of the hat. These clippers are mechanically operated as by a flexible shaft but when they are moved along the hat body a better result is secured when the hat is supported on a slight cushion rather than when it is supported on a wooden hat block and there is less danger of cutting ridges in the hat by the clipper.

55 60 65 70 75 In practice it is customary to have a tube or pipe alongside of the workbench and when the valve 15 is placed on the end of the pipe which is also supplied with a valve, the cover of the hat block is at once inflated due to the small amount of air necessary to inflate it. This is done as the hat body is put on the block.

75 When the hat body is to be removed from the hat block the stem of the valve 15 is pressed against any solid object and air under pressure escapes through the valve and the hat can be removed without pulling or wrinkling it. The cover can be secured by any desired means such as a string or wire 17 which is secured around the groove in the thickened base 18 of the cover.

80 85 90 95 In Figure 2 I show a modification in which the cover 19 is a single piece of flexible material larger than the block, to a slight extent, and fastened to the base of the block so that it is airtight, as for instance, by the ring 20 and the nails 21. This cover can, in practice also be supplied with a valve through which air can be passed to inflate or deflate the cover as will be evident.

It will also be evident that slight changes can be made in the construction of the device without departing from the scope of the invention.

I claim:—

A hat block comprising a block portion of a shape approximately that of a hat to be

100

operated upon, a flexible covering portion slightly larger than the block portion and means for admitting fluid under pressure between said portions to slightly expand the size of the block and provide a slight cushion effect.

In testimony whereof I affix my signature.

FERDINAND E. KAUFFMANN.
